UNITED STATES PATENT OFFICE.

LOUIS STOCKSTROM, OF ST. LOUIS, MISSOURI, ASSIGNOR OF ONE-HALF TO
CHARLES A. STOCKSTROM, OF SAME PLACE.

DESIGN FOR A VAPOR-STOVE.

SPECIFICATION forming part of Design No. 21,652, dated June 21, 1892.

Application filed February 16, 1892. Serial No. 421,753. Term of patent 7 years.

To all whom it may concern:

Be it known that I, LOUIS STOCKSTROM, of the city of St. Louis, in the State of Missouri, have invented and produced a new and original Design for Vapor-Stoves, of which the following is a specification, reference being had to the accompanying drawing, forming part thereof.

The drawing is a perspective view of the stove, showing the novel features of the design.

The leading features of my design consist of a body of parallelopipedon shape, a top plate projecting over the body, a back plate above the top plate, and a door in the front of the body.

1 represents a body, of parallelopipedon shape, having an inclosed lower portion 1^a.

4 are feet forming a support for the body.

3 is the front wall, and 2 the side walls, of 20 the body.

5 is a top plate projecting over the body.

6 are spider-frames located in the top-plate openings.

7 are cylindrical portions within the body. 25

8 is a back plate.

9 is a cylindrical body forming a top ornament.

12 represents a door in the front of the body. 30

15 is a panel beneath the door.

I claim as my invention—

The design for a vapor-stove, substantially as shown and described.

LOUIS STOCKSTROM.

In presence of—

A. M. EBERSOLE,

ED. S. KNIGHT.
